GLASSWARE RACK

Stephen J. Loska, Jr., 1694 Van Buren Ave., Des Plaines, Ill., and Homer J. Hollibaugh, 32 E. Medill Ave., Northlake, Ill.

Filed Mar. 10, 1964, Ser. No. 78,940

Term of patent 14 years

(Cl. D44—29)

FIG. 1 is a perspective view of a glassware rack showing our new design;

FIG. 2 is a side elevational view thereof;

FIG. 3 is a top plan view thereof; and

FIG. 4 is an end elevational view thereof.

We claim:

The ornamental design for a glassware rack, as shown.
